REAR AXLE KICK STAND

Robert F. Humlong, 46 Bryant Circle,
Maysville, Ky. 41056

Continuation-in-part of design application Ser. No. 20,046,
Nov. 12, 1969. This application Sept. 10, 1970, Ser.
No. 24,911

Term of patent 14 years

Int. Cl. D12—16

U.S. Cl. D90—18

FIG-1

FIG-2

FIG-3

FIG-4

FIG-5

FIG. 1 is a front perspective view of the rear axle kick stand showing my new design.

FIG. 2 is a side elevational view of the same.

FIG. 3 is a front elevational view.

FIG. 4 is a rear elevational view.

FIG. 5 is a top plan view of the same.

FIG. 6 is a front perspective view of a modification of my design.

FIG. 7 is a rear perspective view of FIG. 6.

This application is a continuation-in-part of copending application Ser. No. D. 20,046, filed on Nov. 12, 1969, now abandoned.

I claim:

The ornamental design for a rear axle kick stand, as shown and described.
